HYDRAULIC CONTROL MECHANISM

Paul C. Temple, Decatur, Ill., assignor to A. W. Cash Company, Decatur, Ill., a corporation of Delaware

Application October 31, 1941, Serial No. 417,283

2 Claims. (Cl. 60—54.5)

This invention relates to hydraulic control mechanism, and more particularly to mechanism adapted to transmit motion from one element to another element remote therefrom, through the medium of a hydraulic fluid.

A mechanism of this type includes a sender or compressor unit, and a receiver or motor unit. It is desirable that the motor unit should remain stationary except at such times as motion is imparted thereto by actuating the compressor unit. As a practical matter, however, it is very difficult to avoid some slight leakage of the hydraulic fluid when sliding parts, such as pistons, plungers, and the like are employed, particularly when the motor unit is connected to an unbalanced load which requires a continuous force to hold it stationary. Consequently there is a tendency for the motor unit to drift slowly out of position.

It is accordingly one object of the invention to provide a hydraulic control mechanism including a sender and a receiver, with simple and dependable means to prevent the receiver from moving out of position unless it is being actuated by the sender.

It is a further object of the invention to provide a hydraulic control mechanism including a manually operable sender and a receiver, with simple and dependable means whereby the operator may control the movements of the receiver and ensure its remaining stationary when no movement is desired.

With these and other objects in view, as will be apparent to those skilled in the art, the invention resides in the combination of parts set forth in the specification, and covered by the claims appended hereto.

Referring to the drawing illustrating one embodiment of the invention, and in which like reference numerals indicate like parts,

Fig. 1 is a somewhat diagrammatic view of a hydraulic control mechanism connected to a damper, with certain parts shown in section on the line 1—1 of Fig. 2; and

Fig. 2 is a section on the line 2—2 of Fig. 1.

The embodiment illustrated comprises a sender or compressor unit 10 and a receiver or motor unit 11. The sender 10 includes a hollow casing 12 having a removable cover plate 14 and forming a reservoir for a suitable hydraulic fluid such as oil. Two vertical cylinders 15 and 16 are secured to the bottom wall of the casing 12, with the upper portions of the cylinders extending into the casing. The upper ends of the cylinders are open. Within the cylinders 15 and 16 there

are mounted two slideable pistons 18 and 19 respectively. These pistons are joined by connecting rods 20 to the opposite ends of a rocker arm 22 secured to a horizontal shaft 23. This shaft is supported in two spaced bearings 24 in the casing 12. One end of the shaft extends outside the casing, and to this end there is secured an upwardly extending handle or lever 26 which can be swung back and forth to oscillate the shaft and thereby actuate the pistons 18 and 19. Each of the cylinders 15 and 16 is provided with a port 27 in the wall thereof so located that it will be uncovered when the corresponding piston is raised to its uppermost position. These ports open into the interior of the casing 12, and they make it possible for air to escape from the cylinders and for oil to enter the same.

The receiver 11 comprises a hollow casing 28 having a bearing 29 therein for the support of a horizontal rotatable shaft 30. This shaft extends outwardly from the casing through a stuffing box 32. On the outer end of the shaft there is mounted an arm 33 which is connected by a link 34 to the operating arm 36 of a valve or damper 37 arranged to control the flow of fluid in a duct 38. A horizontal cylinder 40 is secured to the casing 28, the outer end of the cylinder being closed and its inner end being open and communicating with the interior of the casing. Within the cylinder there is mounted a slideable piston 41 which is joined by a connecting rod 42 to an arm 43 secured to the shaft 30 within the casing 28. As the piston 41 moves from one end of the cylinder 40 to the other it will oscillate the shaft 30 and the arm 33, and this in turn will actuate the damper 37.

The receiver piston 41 is actuated by hydraulic pressure resulting from movement of the sender pistons 18 and 19. For this purpose the lower end of the cylinder 15 is connected by a pipe 45 to the outer end of the horizontal cylinder 40, and the lower end of the cylinder 16 is connected by a pipe 46 and passageway 47 to the inner end of the cylinder 40. This passageway 47 is formed partly in the cylinder 40 and partly in the casing 28. The cylinder 40 is provided with two ports 49 and 50 which are so located as to be respectively uncovered by the piston 41 when it reaches its outward and inward travel limits. The port 49 is connected to the outer end of the cylinder by means of a passageway 51, and the port 50 is connected to the inner end of the cylinder by the heretofore described passageway 47. In order to prevent fluid from entering the cylinder through these ports 49 and 50, they

are provided with spring loaded check valves 53 and 54 respectively.

It will now be apparent that if the handle 26 is moved to lower the piston 18, oil will be forced through the pipe 45 into the outer end of the cylinder 40, moving the piston 41 inwardly. If the piston 41 reaches its inner travel limit before the piston 18 reaches the bottom of its stroke, the piston 18 can nevertheless be made to complete its travel since the extra oil can escape through the port 50 and past the check valve 54. Similarly, if the handle 26 is moved in the opposite direction to lower the piston 19, oil will be forced through the pipe 46 into the inner end of the cylinder 40, moving the piston 41 outwardly. In case the piston 41 completes its full outward stroke before the piston 19 is at the bottom of its stroke, the latter piston can continue to move since the check valve 53 will open to allow escape of the extra oil through the port 49. Thus the piston 41 and the damper 37 can be moved to any desired position by merely moving the handle 26.

In many cases it is important to hold the damper 37 or other controlled device in a fixed position in spite of unbalanced forces tending to cause movement thereof. For this purpose it has been proposed to provide means for clamping the operating handle (such as the handle 26) in a desired position of adjustment. It is found, however, that with such a construction some movement of the receiver piston will nevertheless occur even with the sender pistons stationary, since a slight leakage of the oil is unavoidable. Hence after a prolonged period it will be found that the damper or other device has moved considerably out of position. The present invention avoids this difficulty.

Referring now to Fig. 2, it will be seen that a stationary cylinder 56 is connected to the receiver casing 28 by means of struts 57, this cylinder surrounding the shaft 30 between the casing 28 and the arm 33. The outer end or head of the cylinder 56 is shaped to provide a bearing 58 for the shaft 30. Within the cylinder there is mounted a piston 60 which is secured to the shaft 30 to prevent relative rotation between the shaft and the piston. These various parts are so constructed and arranged that by supplying pressure fluid to the cylinder 56 it is possible to hold the piston 60 firmly against the inner end of the cylinder, the resultant friction preventing rotation of the piston, as well as the shaft 30. A pipe 62 is connected to the cylinder 56, and it will be understood that this pipe may lead from a compressed air tank or other suitable source of pressure fluid. The piston 60 and cylinder 56 forms a fluid-actuated friction brake or locking device for the shaft 30.

Means is provided whereby the operator may release the receiver from the restraining effect of this locking device when he wishes to impart motion to the damper 37. This may be accomplished by relieving the air pressure in the cylinder 56. For this purpose the pipe 62 is provided with a restriction in the form of an orifice plate 63, and manually controlled means is provided to allow air to escape from the cylinder at a faster rate than it can enter through the orifice. As shown in Fig. 2, one end of the sender shaft 23 extends through annular sealing means

65 into a chamber 66 formed in a hollow plug 67 screw-threaded into the casing 12 in alignment with the shaft. This chamber is connected by a pipe 69 to the pipe 62 at a point between the orifice plate 63 and the cylinder 56. A passage 70 extends longitudinally through the shaft 23 and connects with a passage or chamber 71 in the handle 26, this latter passage leading to a valve 73 which can be opened by means of a push button 74 mounted in the upper end of the handle. The valve is normally held closed by a coiled compression spring 75, and when it is opened air is free to escape from the passage 71 into the atmosphere.

The operation of the invention will now be apparent from the above disclosure. With the valve 73 closed, the air pressure in the cylinder 56 of the receiver 11 will be equal to that in the tank or other source of supply, and the piston 60 will be held firmly against the end wall of the cylinder, effectually preventing any rotation of the shaft 30 or movement of the damper 37 connected thereto. By depressing the push button 74 the operator can open the valve 73 and allow the air to escape from the cylinder 56 through this valve to the atmosphere at a much higher rate than it can enter through the orifice plate 63. Consequently the air pressure in the cylinder 56 will be so greatly reduced that the piston 60 will offer negligible resistance to the rotation of the shaft 30, and it will be possible to actuate the receiver by simply moving the sender handle 26. When the damper 37 has been moved to the position desired, the operator will release the push button 74, allowing the spring 75 to close the valve 73. The air pressure in the cylinder 56 will thereupon increase, and the brake will be applied to hold the damper fixed in its new position.

Having thus described my invention, what I claim as new and desire to secure by Letters Patent is:

1. Hydraulic control mechanism comprising a hydraulic motor having a shaft, a compressor unit, means to conduct hydraulic fluid from the compressor unit to the motor to turn the said shaft, a cylinder surrounding the shaft, a piston within the cylinder and connected to the shaft to turn therewith, means to deliver pressure fluid to the cylinder to hold the piston firmly against one end of the cylinder and thereby prevent rotation of the piston and shaft, and manually controlled means associated with the compressor unit to relieve the pressure in the cylinder.

2. Hydraulic control mechanism comprising a hydraulic motor, a compressor unit having a pivotally mounted operating lever of hollow construction shaped to provide a chamber therein, means to conduct hydraulic fluid from the compressor unit to the motor to actuate the same, a locking device associated with the motor to restrain movement thereof and arranged to be actuated by compressed air, a restricted conduit to supply compressed air continuously to the locking device, a conduit connecting the locking device with the said chamber, and a manually operable valve mounted on the lever to allow discharge of air from the chamber to the atmosphere.
